(57) **CLAIM**

The ornamental design for an apparatus for pulling and lifting wire mesh, as shown and described.

DESCRIPTION

FIG. 1 is a perspective front view of the apparatus for pulling and lifting wire mesh, showing my new design;

FIG. 2 is a perspective back view thereof;

FIG. 3 is a front view thereof;

FIG. 4 is a rear view thereof;

FIG. 5 is a left side view with the right side view being a mirror image thereof;

FIG. 6 is a top side view thereof; and,

FIG. 7 is a bottom side view thereof.

The broken line showing of wheels is included for the purpose of illustrating environment and forms no part of the claimed design.
